UNITED STATES PATENT OFFICE

HENRI COLOMB, OF TAVANNES, SWITZERLAND

MULTIPLE DRAW PLATE AVAILABLE TO THE MANUFACTURE OF ARTIFICIAL SILK

Application filed November 19, 1928, Serial No. 320,444, and in Switzerland November 25, 1927.

The present invention relates to multiple draw plates available to the manufacture of artificial silk.

The draw plates through which the viscose is compressed in the manufacture of the artificial silk have just as many holes as there are threads to be assembled for forming a twist which may be worked. The holes of these draw plates are drilled into the same piece of metal generally at the bottom of a pocket at the end of a conduit admitting the viscose to the coagulating bath. The holes of the several draw plates have to be very fine and thoroughly polished. Their number may be 15 or 20 and it will be easily understood that mistakes in drilling or accidents while the draw plate is nearly finished will cause much waste.

The object of the present invention is to provide a draw plate of the kind described here above and having independent draw plate heads held in a metallic device and which by means of a screw thread are fixed in the wall of the draw plate through which the jets of viscose must pass. This arrangement allows to use draw plate heads which may be given one after the others the dimensions and the polish needed for obtaining a first class thread by means of suitable machines.

Several working forms of draw plates according to the present invention are shown in the annexed drawing. They are shown however only in part the drawing plate heads being sufficient for comprehending the following.

The Figure 1 represents the first working form in section. This form is shown in plan in Fig. 2.

The Figures 3 and 4 are analogous views of a second form. The Figure 5 shows separately two pieces assembled in the working form shown in Figures 6 and 7.

The Figures 8, 9 and 10 relate to a fourth working form and show it in an axial section, and end view and a plan view respectively. The end view according to Fig. 9 is taken from the underside of the plug *g* with a portion of plate *a* cut away.

A threaded hole *f* is cut into the wall *a* of

the multiple draw plate and a hollow screw plug *g* is introduced into this hole. The hollow inside of screw plug *g* comprises a conical and a cylindrical part. At the bottom of the latter a perforated stone *c* which could also be replaced by a metallic screw plate head is maintained by means of an elastic plug *d* pressed against the cylindrical walls of the hole. The screw head *g* is octagonal so that the whole draw plate head 55 may be taken out by means of a wrench in order to machine it on high speed machines for calibrating its hole and giving to the latter the needed polish for obtaining a perfect thread. 60

In the working form of the Figures 3 and 4 the hollow screw plug *g* comprises likewise a conical part extended into a cylindrical part. The stone *c* however is introduced forcibly into the bottom of its lodging. It 70 is maintained thereby the elasticity of the walls of the hollow screw plug. 65

In the working example of the Figures 5, 6, and 7 the hollow screw plug *g* possesses at its end a lodging *h* having a larger diameter 75 than the axial perforation and in said lodging the draw plate head *c* is maintained by the chased ends of the screw plug. 75

This chasing may be effected by any means employed by watchmakers for engraving stones in metal. The axial hole of the screw plug is square so that the whole may be unscrewed and replaced at will by means of a key. 80

In the working form of the Figures 8, 9, 85 and 10 the wall *a* of the multiple draw plate is not threaded on its whole thickness. The screw hole ends with a conical hole into which comes to bear the end *i* of the screw *g*. This end is likewise conical and split 90 into four segments which are slightly elastic thus forming a pinch into which the draw head *c* is introduced. By screwing the screw tight the pinch will be closed and the 95 stone be held fast.

In all the described working forms there is a stone *c* constituting the head of the draw plate but it is easily understood that this stone could be replaced by an analogous 100

metallic cylinder having the same form and rendering the same services.

The hollow screws employed in the described examples could be replaced by tubes having a cylindrical or conical smooth outside surface and introduced forcibly like an enchased stone into a corresponding hole of the wall of the draw plate.

What I claim is:

- 10 1. In a multiple draw plate available to the manufacture of artificial silk, a wall plate having a threaded hole, an elastic hollow screw plug fitted into this hole and having a polygonal head for a wrench, a conical part in the hollow of the plug and a cylindrical part adjoining it and intended as a lodging for a draw plate, a draw plate comprising a fine stone having a central aperture for the jet of viscose and engravings means adapted to secure the working position of the stone.
- 15 2. In a multiple draw plate available to the manufacture of artificial silk, a wall plate having a threaded hole, an elastic hollow screw plug fitted into this hole and having a polygonal head for a wrench, a conical part in the hollow of the plug and a cylindrical part adjoining it and intended as a lodging for a draw plate, a draw plate comprising a fine stone having a central aperture for the jet of viscose and engravings means for securing the stone, said means comprising an engravings bottom edge of the cylindrical hollows and a perforated elastic plug engravings in the same cylindrical hollow on top of the stone.

In testimony whereof I affix my signature.

HENRI COLOMB.
